US00D971681S

(12) **United States Design Patent** (10) Patent No.: **US D971,681 S**
(45) Date of Patent: **** Dec. 6, 2022**

(54) **DECANTER**

(71) Applicant: **LUXURY HOLDINGS LLC**,
Brooklyn, NY (US)

(72) Inventor: **Yisroel Lefkowitz**, Brooklyn, NY (US)

(73) Assignee: **LUXURY HOLDINGS LLC**,
Brooklyn, NY (US)

(**) Term: **15 Years**

(21) Appl. No.: **29/796,799**

(22) Filed: **Jun. 27, 2021**

(51) LOC (13) Cl. **07-06**

(52) U.S. Cl.

USPC **D7/598**

(57) **CLAIM**

The ornamental design for a decanter, as shown and described.

DESCRIPTION

FIG. 1 is a perspective view of a decanter, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the decanter that form no part of the claimed design.

1 Claim, 7 Drawing Sheets
